UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CENTERING DEVICE FOR CAR COUPLERS.

Application filed September 30, 1926. Serial No. 138,703.

Reference is had to the accompanying drawings, which illustrate the preferred form of the invention, though it is to be understood that the invention is not limited 5 to the exact details of construction shown and described, as it is obvious that various modifications thereof within the scope of the claims will occur to persons skilled in the art.

10 This device is an improvement of the centering device for car couplers as described in my co-pending application Serial No. 562,505, filed May 20, 1922, which device comprises a coupler supported upon a carrier swingingly suspended by links to a member on the car. In this co-pending application I have described and claimed a construction wherein the links cannot be removed from their associated parts before 20 the coupler is removed from the car. However, there are conditions necessitating the removal of the carrier, or one or both of the links, without removing the coupler from the car. To remove the coupler from 25 the car it must be detached from the draft gear which is difficult and expensive or the draft gear must be removed with the coupler which is even more difficult and expensive.

To meet such conditions it is expedient to 30 provide means to permit the removal of one or both of the links from the car (which also permits the carrier to be removed) which means also prevents the links, or either of them, from jumping out of their 35 pockets by impact of the cars and foul the device. My invention relates to such a construction.

In the drawings:

Fig. 1 is an elevation of my device applied to a railway car.

Fig. 2 is a section on line 2—2 of Fig. 1.

Fig. 3 is a side elevation of Fig. 1.

Figs. 4 and 5 show a modified form.

The striker 1 or other member is attached 45 to the car in any desired manner and the coupler carrier 2 is suspended from the member 3 by links. These links preferably have T heads 4 at each end engaging bearings in the carrier and member, respective-

ly. The T heads at both ends of one link 50 (5) and at one end of the other link (6) are so positioned and dimensioned that they cannot be removed from their respective bearings before the coupler is removed from the car. A clip 7 or other device is secured, 55 preferably to the striker, forming removable means, which means is so positioned that the T head at the other end of the other link 6 cannot be removed from its bearing before the coupler is removed from the car 60 or until such means is removed. This clip or other device is also positioned so that the T head of the other link (6) cannot jump out of its bearing while the coupler is in operative position. The depth of the 65 bearings in the striker and carrier, respectively, is greater than the vertical distance between the top of the coupler shank 8 and the upper wall 9 of the opening in the striker.

Figs. 4 and 5 show a modified form. A 70 horizontal bolt 10 is used for the purpose specified which is removably secured to the striker.

I claim:

1. The combination in a railway car of a 75 coupler, a member restricting the upward movement of the coupler, a coupler carrier, and links swingably suspending the opposite ends of the carrier to said member, one 80 of said links having a T head at its upper end engaging bearings in said member of less depth than the distance between the top of the coupler shank and the adjacent face of said member.

2. The combination in a railway car of a 85 coupler, a member restricting the upward movement of the coupler, a coupler carrier, links swingably suspending the opposite ends of the carrier to said member, one of 90 said links having a T-head at its upper end engaging bearings in said member of less depth than the distance between the top of the coupler shank and the adjacent face of said member, and removable retaining 95 means for holding the T-head in place during service.

GARTH G. GILPIN.
